Inventor:

UNITED STATES PATENT OFFICE

EDWIN J. SANTEE, OF ST. LOUIS COUNTY, MISSOURI

DESK

Application filed June 16, 1927. Serial No. 199,218.

This invention relates generally to desks, and has more particular reference to desks of the type commonly used in schools and provided with an anterior seat for the pupil who uses the next preceding desk, the desks being arranged in forwardly to rearwardly extending rows. Certain features of the invention, however, are applicable to desks in general, and some are capable of still more extended or of individual use, as will hereinafter more fully appear.

One of the objects of the present invention is to provide a desk of the character described that can, after being secured to the floor, be easily turned to face the rear or either side of the room. When the desks face the rear, the seats alternate with the desks in the row, so that the pupils can be seated for writing. When the desks face either side, they may not be positioned conveniently with relation to the seats for writing, but the pupils may be seated comfortably to observe a class or board demonstration at the side of the room.

Another object is to provide means for preventing the desk from being turned unintentionally.

Another object is to provide a desk that may be collapsed to diminish its horizontal dimensions, so that the floor will be more accessible for sweeping or scrubbing, so that the aisles between the rows of desks may be widened for drilling or marching, and so that the desk will occupy a minimum of space when it is being shipped or stored.

Another object is to provide a desk whose top and seat can be folded when not in use to protect them from dust and from being marred.

Another object is the provision of simple adjusting means whereby the height of the seat or desk may be quickly and easily changed to make a perfect seating for every pupil, irrespective of whether the length of the body of the pupil is in greater or less proportion to the length of his limbs.

Another object is the provision of a desk that can be readily unpacked and set up on the floor, and as quickly taken up and repacked.

Another object is the provision of means for securing the desk to the floor so that after its removal therefrom the floor will be free of unsightly holes or projections.

Another object is to provide a desk that is supported from the floor in such a way that there are no standards or legs positioned to interfere with the pupil when he sits down or arises from the desk.

A further object is to provide a desk that is quiet, comfortable, strongly built, simple, and inexpensive.

Other objects and advantages will appear in the course of the following description of divers embodiments of the invention that have been selected for the purpose of illustration only and not in a limiting sense.

In the accompanying drawings forming part of this specification, in which like numbers of reference denote like parts wherever they occur,

Figure 1 is a plan view of one form of desk embodying this invention;

Figure 2 is a similar view of the same as it appears when collapsed and turned to face the side of the room;

Figure 3 is a side elevation of the desk, looking in the direction of the arrow on Figure 1;

Figure 4 is a rear elevation of the same;

Figure 5 is a fragmentary plan view of the pedestal that supports the desk;

Figure 6 is a plan view of the set collar that may be adjusted on the pedestal to determine the height of the desk;

Figure 7 is a horizontal sectional view taken on the line 7—7 in Figure 9;

Figure 8 is a fragmentary horizontal sectional view of the vertically adjustable seat-supporting bracket, taken on the line 8—8 in Figure 3;

Figure 9 is a vertical central sectional view taken through the pedestal on the line 9—9 in Figure 5;

Figure 10 is a fragmentary view of another form of desk made in accordance with this invention, looking in the direction of the arrows 10 in Figure 12, but with the top retracted;

- Figure 11 is a fragmentary view taken looking in the direction indicated by the arrow 11 in Figure 12, but with the top retracted;
- 5 Figure 12 is a fragmentary vertical transverse central sectional view of the same; but with the top extended;
- Figure 13 is a fragmentary plan view of a third embodiment of the invention;
- 10 Figure 14 is a fragmentary side view of the same, looking in the direction indicated by the arrow in Figure 13;
- Figure 15 is a fragmentary plan view of a fourth specific form of the invention, as it appears when extended;
- 15 Figure 16 is a fragmentary sectional view taken on the line 16-16 in Figure 17;
- Figure 17 is a side elevation of the desk of Figure 15; and
- 20 Figure 18 is a fragmentary vertical sectional view taken on the line 18-18 in Figure 15.
- The various forms of desks exhibited in the drawings preferably have the same form 25 of supporting means, comprising a base 1, and a frame 2 rotatable thereon. The upper portion of frame 2 is preferably formed of a channel-shaped bar 3 of iron or other suitable metal, bent into U-shape, so that 30 the channel is on the inside. The intermediate horizontal arm 4 of the bar 3 is bolted or otherwise suitably secured to the flanges or ears 5 that extend laterally from the upper end of the tubular casting 6 that 35 forms the lower portion of the frame 2. The base or post 1 preferably comprises a hollow cylindrical upper portion 7 having a closed upper end 8 that is provided with a central aperture for the passage there- 40 through of a bolt 9; and a flaring hollow lower portion 10 that develops downwardly into an open bottom of elliptical formation. The lower portion 10 is offset or enlarges laterally from the upper portion 7 to form 45 an upwardly facing transverse shoulder 11, on which to seat a collar 12, that fits slidably on the upper portion 7. The collar 12 is provided with a set screw 13, by means of which it can be affixed to the tubular portion 7 at any desired height. The portion 7 is preferably provided with a vertical series 50 of alternative seats or depressions 14 in its peripheral surface 15, in which the inner end of the set screw may be anchored, so that the grip afforded by the set screw may be made more secure and may be effected without producing burrs or deformations on the peripheral surface 15. The lower end of the screw 9 is received by an internally 55 screw-threaded hole 16 that is disposed centrally through a plate 17 and a boss 18, formed integral with and depending from the under side of the said plate. The plate 17 is countersunk in the floor centrally of 60 the post and so that its upper face 19 is flush with the floor surface 20. The plate 17 is secured to the floor 20 by means of countersunk screws 21 that pass through a marginal series of openings therefor in the plate 17. The collar 12 presents an annular series of teeth 22 on its upper face 23 that are adapted to intermesh with an annular series of teeth 24 on the lower end face 25 of the tube 6.
- U-shaped brackets 25 have their posterior arms 26 secured to the lateral arms 27 of the frame 3 by means of screws 28 that screw into the arms 27 and pass through vertically elongated slots 29 in the arms 26. The arms 26 are provided with horizontally extending teeth 30 that intermesh with horizontally extending teeth 31 on the arm 27 to prevent slippage of the brackets on the arms 27 when the arms and brackets are drawn together by the screws 28. The anterior arms 32 of the brackets 25 are pivoted to the seat 33 preferably through a hinge 34 of the ball and socket type, best shown in Figure 8, the seat brackets 35 having lateral projections 36 that are adapted to engage the arms 32 of the U-shaped brackets 25 to limit the descent of the seat.
- A back 37 for the seat 33 is secured to the anterior sides of the upright arms 27 of the frame 3; and a bookrack 38 is affixed to the posterior sides of the arms 27. Referring now more particularly to the form of the invention exhibited in Figures 1 to 4, inclusive, the rack comprises a wall 39 abutting against the arms 27, a bottom wall 40, side walls 41, and a front wall 42. Rearwardly projecting brackets 43 and 44 are welded or otherwise suitably secured to the upper ends of the posterior sides of respective arms 27. The right-hand bracket 43 enlarges inwardly at its upper end to form a seat 45 for an inkwell 46, that projects through an aperture 47 in the top 48 of the desk. The top 48 is recessed anteriorly in each lateral edge to accommodate L-shaped arms 49, secured thereto by screws 50, and provided with sockets or holes 51 in their vertical arms 52 pivotally to receive pins 53, affixed in any suitable manner in the lateral edges of the back 37, the said edges being recessed to provide clearance space for the arms 52.
- When in use, the desk is extended, and normally it faces the front of the room, as shown in Figure 1, the front of the room being assumed, for the purpose of illustration, as being at the right of the figure. It will be observed that the base 10 of the pedestal 1 is secured to the floor so that the major axis of its elliptical bottom extends in a forward-to-rearward direction, thereby allowing ample room on each side of the base for the respective legs and feet of the user of the desk, while at the same time the desk possesses the greatest stability in the direction in which it is the more liable to be tilted.

When it is desired to arrange the desks so that they will face the rear or either side of the room, the desk is lifted slightly to disengage the intermeshing teeth 22 and 24 and is then turned in the desired direction, 5 after which it may be allowed to drop to effect re-engagement of adjacent teeth 22 and 24 to prevent unintentional turning of the desk from its new position. When the desk is not in use, the top 48 may be tilted upwardly and folded over the back 37, and the seat 33 may be folded back, as shown in dotted lines in Figure 3, thereby protecting the top and seat from dust and from being marred. It will be observed that, 10 since the inkwell 46 is supported independently of the tiltable top 48, it is not disturbed when the top is lifted and folded, and yet is accessible through the opening 47 when the top is in its normal position. The rearward retraction of the seat 33 and the forward retraction of the top 48, as indicated by the dotted lines in Figure 3, diminishes, also, the front-to-rear horizontal 15 dimensions of the desk, so that the floor is more accessible for sweeping or scrubbing. When the seat 33 and top 48 are retracted and the desk is, also, turned to face the side of the room, as illustrated in Figure 2, the horizontal dimensions of the desk are diminished in all directions, thereby, also, 20 economizing floor space on the sides of the desks to widen the aisles for drilling or marching. In this position, the desk, also, occupies a minimum of space for shipping 25 or storing. The height of the top 48 may be varied by vertically adjusting the collar 12 on the tube 7, or by substituting another collar of different height and allowing it to rest on the shoulder 11. The height of 30 the seat may be varied by vertically adjusting the brackets 25 on the arms 27. It will be observed that the desks may be easily removed from the floor by simply lifting them from their bases 10 and unscrewing 35 the screws 9 from the floor plates 17, after which the opening 16 in the plate may be easily plugged, so that the floor will remain free of unsightly holes or projections, as 40 would have occurred if the desks had been secured to the floor in the conventional manner.

Figures 10 to 12 inclusive, illustrate another form of retractile top for the desk. 45 The underside of the top 54 bears a rod 55 disposed parallel to and equidistant from the lateral edges 56 of the top. The upturned ends 57 of the said rod are secured in any suitable manner to the top 54, so that 50 a space 58 intervenes between the top 54 and the rod 55 to accommodate the intermediate portion of the U-shaped loop 59, whose ends 60 are secured in the wall 61 of the bookrack 62. The lateral edges 56 are adapted to 55 slide in and to be guided by the channels 63 of the arms 27 of the frame 3. When the desk is in use, the top 54 is extended as shown in full lines in Figure 12, and rests on the top edges of the lateral walls 64 of the bookrack 62, the top being prevented from 60 tilting upwardly at its forward edge by reason of its engagement with the underside of the bead 65 that is secured to the rear face of the back 37. The lateral edges 56 are recessed at their forward ends 66 to accommodate the arms 27 when the top is extended, and studs 67 project laterally from the recessed edges 66 into the channels 63. To 65 retract the top 54, its rear end is tilted upwardly until the top is in the plane of the grooves 63, and it is then lowered to the position shown in Figures 10 and 11, and indicated in broken and dotted lines in Figure 12. The rod 55, being guided by the loop 59, tends to prevent lateral tilting and 70 binding of the top 54 in the grooves 63.

The form of top shown in Figures 13 and 14 comprises an anterior section 68, affixed to the top of the brackets 43, and a posterior section 69, pivoted to the section 68 by means 75 of hinges 70. When the section 69 is extended, it rests on the rear portion of the brackets 43; and, when the desk is not in use, the section 69 may be swung upwardly and forwardly to the dotted position shown 80 in Figure 14.

Referring now to the form shown in Figures 15 to 18, inclusive, brackets 71 and 72 are secured in any suitable manner to the respective arms 27, as are, also, the lateral walls 73 of a bookrack 74. The bookrack, also, has a top wall 75, on which is seated the inkwell 46. The top 76 is recessed at 90 77 in the forward portions of its lateral edges 78 to accommodate the brackets 72 and 73 when it is extended as shown in Figures 15, 16, and 17. Grooves 79 extend longitudinally in the inner sides of the brackets 71 and 72 and enlarge upwardly at their forward ends 80. Pins 81 project laterally 100 from the recessed edges 77 and extend into the grooves 79. The top 76 is recessed at 82 to accommodate the inkwell 46. The pins 81 fit slidably but closely in the grooves 79, so that when the top 76 is in its elevated 105 position the pins 81 are seated in the enlargements 80 of the grooves 79, and are prevented by friction from sliding rearwardly.

When the weight of the hand is placed on the rear portion of the top, the 110 top is tilted until the pins 81 bear against the upper faces of the recesses 80, so that rearward sliding of the pins in the grooves is further prevented by reason of their being out of alinement. To retract the top 115 76 to the position shown in Figure 18, it is raised at its rear end to depress the pins 81 out of the recesses 80, and then pulled rearwardly until the pins reach the rear ends 120 of the grooves 79, when the top can be tilted 125 130

to the depending position indicated in Figure 18. If desired, a suitable lock (not shown) may secure the top 76 against the wall 82 of the bookrack 74.

Having thus fully described this invention, I hereby reserve the benefit of all changes in form, arrangement, order, or use of parts, as it is evident that many minor changes may be made therein without departing from the spirit of this invention or the scope of the following claims.

I claim:

1. A desk comprising a frame having a desk top and a seat mounted on said frame, a tubular casing carried by the frame, a base member having a cylindrical upper portion and a shoulder at the lower end of said portion, said cylindrical portion having depressions, a collar mounted upon said cylindrical portion and having a screw adapted to enter one of the depressions, said casing receiving said cylindrical portion and engaging the collar, and a bolt passing through the base and having its head housed in the casing with the upper surface of the head spaced below the upper edge of the casing.
2. A desk comprising a frame having a desk top and a seat mounted thereon, a tubular casing carried by the frame, a base member having a cylindrical upper portion and a shoulder at the lower end of said portion, said cylindrical portion having depressions, a collar mounted upon said cylindrical portion and having a screw adapted to enter one of the depressions, said casing receiving said cylindrical portion and engaging the collar, and the abutting edges of the collar and casing having intermeshing teeth.
3. In testimony whereof I hereunto affix my signature.

EDWIN J. SANTEE.
